UNITED STATES PATENT OFFICE.

CHARLES A. PRESCOTT, OF HUDSON FALLS, NEW YORK.

ASH-TRAY.

1,323,489.

Specification of Letters Patent.

Patented Dec. 2, 1919.

Application filed March 13, 1919. Serial No. 282,276.

To all whom it may concern:

Be it known that I, CHARLES A. PRESCOTT, a citizen of the United States, residing at Hudson Falls, in the county of Washington, State of New York, have invented certain new and useful Improvements in Ash-Trays; and I do hereby declare the following to be a full, clear, and exact description of the invention, such as will enable others skilled in the art to which it appertains to make and use the same.

This invention relates to new and useful improvements in ash trays and has as its prime object the provision of a combined match box and ash tray which may be readily secured to the under side of the arm of a chair, the edge of a table, or other like place where such a device is needed.

A further object is to provide a novel and improved device of this character wherein means are provided for securing the device to the under face of an object or piece of furniture whereby the device may be quickly and easily swung into and out of position beneath the object.

A further object is to provide novel and improved means for holding the device from accidental movement from either its concealed or exposed positions.

Other objects and advantages will be apparent from the following description when taken in connection with the accompanying drawing.

In the drawing:

Figure 1 is a side elevation of the tray associated with the arm of a chair, the tray being shown beneath the arm.

Fig. 2 is a bottom plan view of the tray and the attaching means, the said tray and attaching means being removed from the arm of the chair.

Fig. 3 is a perspective view of the attaching disk, showing the stop lug thereon.

Fig. 4 is a vertical transverse sectional view through the tray.

Fig. 5 is a vertical longitudinal central sectional view through the tray.

Referring particularly to the accompanying drawing, 1 designates the arm of a chair to the lower face of which is secured the disk 3, by means of the round-headed screws 2. Depending from the lower face of the disk, adjacent the edge thereof, and near the outer edge of the arm 1, is a lug 4. Depending from the center of the disk is a pivot pin 5 which has an enlarged head 6

on its outer end. Engaged around the stem of the pin 5 is the loop or eye 7 of the outwardly diverging arms 8, said arms extending in parallel relation to each other beyond the outer ends of the divergent portions, the other ends of the arms being directed inwardly at right angles toward each other as shown at 11. A tray is disposed between the parallel portions of the arms 8 and has its sides rolled on said arms, and one of its ends rolled around the portions 11, as shown in Fig. 5, the rolled edges of the sides being shown at 10. The parallel portions of the arms are designated by the character 9. Extending transversely within the tray is a vertical partition 14, and disposed in the forward compartment is the match receptacle 15, the upper edges of two of its sides and one end being rolled around the portions 9 and a stiffening wire 9'. In the other compartment of the tray there is disposed the receptacle 18 which is adapted to receive ashes, the sides inclined upwardly and outwardly and rolled over the arms 9 and the portions 11. These trays, however, are arranged to be readily removed from the main tray so that they may be cleaned.

It will be noted that the lug 4 is disposed a circular distance from the screws 2 equal to ninety degrees, and is located for engagement by the divergent portions of the arm, so as to limit the pivotal movement of the tray with respect to the disk. Thus, with the disk 3 so fastened to a chair arm, for example, that the lug 4 lies near an edge of the arm, the tray may be swung to engage one of the arms 8 with the lug, when the tray will project beyond the chair arm. When the tray is swung into position beneath the chair arm the arms 8 will flex so as to move past the head of one of the screws 2, and when in such position the head of the engaged screw will prevent accidental outward movement of the tray.

From the foregoing it will readily be seen that I have provided a simple and efficient device which may be secured to a chair arm, table top, or other similar object, without disfiguring the same, and which will normally lie concealed therebeneath. The device can be easily and quickly swung outwardly when needed, and when not being used is swung into concealed position. The construction permits the contents to be emptied without removing the entire device.

The portions of the wire, at 11, are

twisted together and extended outwardly and downwardly, as at 20 in the form of a hook, which is adapted to be engaged by a finger of the operator's hand to move the device out from beneath the edge of the table or to replace the same therebeneath.

What is claimed is:

1. The combination with a support, of a disk secured to the lower face of the support and having a depending lug on its lower face adjacent and edge of the support, fastening means for securing the disk to the support and having projecting heads, a tray having outwardly extending integral converging arms of resilient material, said arms terminating in a common loop, and a pin extending downwardly from the center of the disk for the pivotal reception of the said loop, whereby the tray is capable of swinging movement into and out of position beneath the support, the lug being located for engagement with the resilient arms to limit movement of the tray while the head of one of the fastening means is located so as to engage between said arms to releasably hold the tray beneath the support.
2. An ash tray for attachment to the under faces of articles of furniture in a way to be swung into and out of position to lie beneath such furniture and to be closed thereby, consisting of an attaching plate having an opening for the reception of an attaching device for securing the plate to a support, an attaching device in said opening, a member pivotally connected with the plate against the lower face thereof and in-

cluding a resilient portion shiftable, through pivotal movement of the member, across the attaching device, said attaching device having a portion extending below the lower face of the plate and into the plane of the pivoted member and an open topped receptacle carried by the member and lying with its upper edge substantially in the plane of the upper face of the plate.

3. An ash tray for attachment to the undersurfaces of articles of furniture in a way to be swung into and out of position to lie beneath such furniture, consisting of a receptacle, resilient arms carried by the receptacle, means for connecting the arms to an article of furniture for pivotal movement of the receptacle to lie at times beneath the article of furniture and at times to extend outwardly therebeyond and a pin constituting a part of the means for attaching the arms to an article of furniture, said pin extending into the path of movement of the arms, said arms by reason of their resilience, being movable over the pin to lie with the pin between the arms, said pin being so located that when it lies between the arms, the receptacle will lie in a predetermined position, by which structure and arrangement the pin acts to hold the receptacle yieldably in such position.

In testimony whereof, I affix my signature in the presence of two witnesses.

CHARLES A. PRESCOTT.
